THREE-DIMENSIONAL GAME BOARD OR SIMILAR ARTICLE

Harry Zelenko, 240 E. 61st St.,
New York, N.Y. 10021

Filed July 20, 1973, Ser. No. 381,027

Term of patent 7 years

Int. Cl. D21—01

U.S. Cl. D34—5 SS

FIG. 1

FIG. 3

FIG. 2

FIG. 1 is a perspective view of a three-dimensional game board or similar article showing my new design;

FIG. 2 is a side elevational view; and

FIG. 3 is a top plan view.

I claim:

The ornamental design for a three-dimensional game board or similar article, substantially as shown.
